UNITED STATES PATENT OFFICE

ABRAHAM A. SCHIMMEL, OF BROOKLINE, MASSACHUSETTS

COVER FOR BED SPRINGS AND THE LIKE

Application filed July 26, 1928. Serial No. 295,608.

My invention relates to covers for bed-springs and the like and it has for its object to provide an improved article of this kind.

Covers for bed springs and the like have heretofore been provided made from textile fabric, usually ticking, consisting of a bag-like structure that could be opened at one end to permit the insertion therein of the bed spring, means being provided for holding the cover in position on the bed spring against displacement while in use. As heretofore constructed a cover of this class required an objectionable amount of time and labor to apply the same, or remove it from, a bed spring, and the principal object of my invention is to obviate this objectionable feature. To this and other ends I have provided a cover for bed springs having the peculiar features of construction and mode of operation pointed out in the claim at the close of the following description.

In the accompanying drawings:

Figure 1 is a perspective view of my improved cover for bed-springs and the like as viewed from below.

Figure 2 is a bottom plan view of a corner portion of the cover shown in Figure 1.

Figure 3 is a longitudinal sectional view, more or less diagrammatic, of the cover shown in Figure 1.

Figure 4 is a cross sectional view of the cover shown in Figure 1.

Figure 5 is a section on line 5-5 of Figure 1.

Figure 6 is a detail hereinafter described. Having reference to the drawings, 1 is the top wall or panel of my improved cover for bed-springs and the like; 2, 2 are the side walls of the cover joined at their tops to the opposite sides of the top wall 1; while 3, 3, Figure 3, are the end walls of the cover joined at their tops to the opposite ends of the top wall 1.

At one end thereof the cover is constructed with a bottom wall section or panel 4 that is relatively narrow and extends from one side wall 2 to the opposite side wall 2, the opposite ends of said bottom wall section or panel 4 being permanently joined to the bottom portions of said side walls 2.

At the opposite end of the cover there is provided another bottom wall section or panel 5 which extends from one side wall 2 to the opposite side wall 2, and which is permanently joined along one side to the adjacent end wall 3. Each end of this bottom wall section 5 is provided with a series of lugs or dogs 6 to co-operate with a corresponding series of lugs or dogs 7 provided at the lower edge of the adjacent side wall 2. By means of a cam slide 8 connected with the two series of lugs or dogs 6 and 7 the latter are operated so as to be interlocked as shown in Figure 6, whereby the end of the bottom wall section 5 is securely connected with the adjacent side wall 2, or so as to be disengaged thereby to disconnect the end of the bottom wall section 5 from said side wall.

As shown in Figure 5 the dogs or lugs 6 are permanently secured to a tape 9 which is fastened by means of stitches 10 to the bottom wall section 5, while the lugs or dogs 7 are permanently fastened to the tape 11, which in turn is secured to the adjacent side wall 2 by a longitudinal line of stitches 12. The cam slide 8 is provided with a finger-piece 13 by means of which it is manipulated, and in Figure 2 the cam slide 8 is shown at the limit of its movement toward the left with the two series of lugs or dogs interlocked to fasten the end of the bottom wall section 5 to the side wall section 2. When the cam slide 8 is moved along the series of lugs or dogs toward the right, Figure 2, said two series are unlocked leaving the end of the bottom wall section disconnected from the side wall section 2.

The fastener means, per se, including the lugs or dogs 6 and 7, and the cam slide 8 is old and well known and is fully illustrated and described in Patent No. 1,219,881, granted March 20, 1917, to which reference may be had. When both the cam slides 8, Figure 1, are shifted to the limit of their movement toward the right, the bottom wall section or panel 5 is then only connected with the end wall 3 along its outer side edge, and, therefore, it may be permitted to assume the position shown by dotted lines in Figure 1, which is the case when the cover is being applied

to a bed-spring. In applying the cover to a bed-spring the end of the cover including the bottom wall panel 4 is slipped on to one end of the bed-spring, indicated by dotted lines at 14 in Figure 3, and then after pulling the opposite end of the cover down into position around the opposite end of the bed-spring the two cam slides 8 are slid inwardly, toward the left in Figures 1 and 2, to the limits of their movements in that direction, thereby instantly and by one simple movement of the hand securely connecting the opposite ends of the bottom wall section 5 with the side walls 2, 2, and thus securing the cover in position upon the bed-spring.

In practice the cover is usually made from ordinary ticking, and when applied to a bed-spring serves, as usual, to prevent lint, dust and the like falling on to the floor; but an important function of it is to protect the mattress, which is laid upon the cover, from being marked or stained by the metal bed-spring 14.

From the above description it will be clear that my improved cover can be applied to a bed-spring or removed therefrom in a fraction of the time that has heretofore been required, and furthermore, the above described cover is of very simple, efficient and inexpensive construction.

What I claim is:

A cover of the character described comprising a top wall; two oppositely disposed side walls permanently connected at their tops with the opposite sides of said top wall; two oppositely disposed end walls permanently connected at their tops with the opposite ends of said top wall and permanently connected at their ends to the ends of said side walls; a bottom wall section permanently connected along one side with the bottom of one of said end walls throughout the length of the latter and permanently connected at two other opposite sides throughout their lengths with the bottom portions of said side walls; a narrow transverse bottom wall section permanently connected along one side thereof with the bottom of the other end wall throughout the length of the latter, and means separably connecting the opposite ends of said last mentioned bottom wall section with the adjacent bottom edge portions of said side walls.

Signed by me at Boston, county of Suffolk, and State of Massachusetts, this 20th day of June, 1928.

ABRAHAM A. SCHIMMEL.
